UNITED STATES PATENT OFFICE.

HENRY H. ALLISON, OF FAIRMONT, MINNESOTA; F. J. BROOKER ADMINISTRATOR OF
SAID HENRY H. ALLISON, DECEASED.

BURGLARPROOF DEVICE.

Application filed July 30, 1921, Serial No. 488,603. Renewed February 19, 1925.

To all whom it may concern:

Be it known that I, HENRY H. ALLISON, a citizen of the United States, and a resident of Fairmont, in the county of Martin and 5 State of Minnesota, have invented a certain new and useful Burglarproof Device, of which the following is a specification.

The object of my invention is to provide a burglar proof device of very simple and 10 efficient construction.

More particularly, it is my object to provide a device of the general kind under consideration, whereby a closure member for a vault door and a closure member for a cash 15 box are so arranged that upon the closing of a switch, a circuit may be closed for releasing the closure devices for preventing access to the vault and the cash box.

With these and other objects in view, my 20 invention consists in the construction, arrangement and combination of the various parts of my device, whereby the objects contemplated are attained, as hereinafter more fully set forth, pointed out in my claims, 25 and illustrated in the accompanying drawings, in which:

Figure 1 shows an inside or rear elevation of a bank vault door or the like equipped with a closure member embodying my invention. 30

Figure 2 shows a perspective view of a portion of a bank counter having thereon a cash box equipped with my invention.

Figure 3 shows a vertical, sectional view 35 through the cash box.

Figure 4 shows a detail, sectional view taken on the line 4—4 of Figure 3.

Figure 5 shows a detail, sectional view of the locking device for the door closure member; and 40

Figure 6 shows a diagrammatic view of the electrical connections.

In the accompanying drawings, I have used the reference numeral 10 to indicate 45 generally the wall of the bank vault or the like, in which is provided a door opening 11. On the inside of the vault and spaced laterally from the door opening on opposite sides thereof are mounted upright bars 12.

Pivoted to the bars 12 are laterally projecting members 13. I provide a plurality of the members 13 for each bar 12. Pivoted to each set of members 13 are spaced 50 closure bars 14, 15, and 16. Pivoted to

each closure bar 16 is a locking bar 17 extended through a guide or keeper 18 on the bar 12.

Mounted on the bar 12 below the locking bar 17 is a pin 19 and in the lower edge 60 of the bar 17 is a notch 20. In the upper edge of the bar 17 is a notch 21.

Above the locking bar 17 is a swinging pawl or locking member 22.

When the closure device, just described, 65 is open, the members 13 are inclined upwardly, as shown in Figure 1, and the member 17 is inclined downwardly and laterally as shown in said figure.

It will be seen that the closure device 70 tends to drop by gravity to closed position, and when it does so drop, the members 17 will slide in the guides 18, until the notches 20 register with the pins 19, whereupon the pins 19 will enter the notches 20 and the 75 locking pawls 22 will swing downwardly with their free ends received in the notches 21, so that the bars 17 can not be raised, except by the use of a special tool or by cutting them in two. 80

Above the door opening 11 are two bars 22^a pivoted together at adjacent ends, as at 23, and having near their outer ends, elongated slots 24, in which are received pins 25. When the closure members are raised, as 85 shown in Figure 1, the bars 22^a are arranged substantially in alignment horizontally with their ends abutting against the upper ends of the members 16, between the members 16, as shown in Figure 1. 90

The friction of the parts will hold the closure member open. However, owing to the fact that the great weight of the bars 22^a is between the pins 25, the central portions of the bars 22^a will tend to drop 95 downwardly, when their frictional engagement with the member 16 is released or when forced downwardly in any way.

When the adjacent ends of the bars 22^a are moved downwardly, their outer ends 100 swing upwardly and clear the members 16, whereupon the closure member will drop by gravity to locked position.

Above the bars 22^a is a guide 26, in which is mounted a weight 27, having a head 28. 105 A trigger 29 is pivoted adjacent to the head 28 and has a projecting finger or the like 30, which can be made to stand below a portion of the head 28 for holding the head 28 in its raised position. 110

Adjacent to the trigger 29 is a solenoid 31, having an armature 32. The solenoid is connected in an electric circuit by means of wires 33 and 34 with a source of electrical energy 35 and a switch 36.

I have shown a portion of a bank counter 37 on which is placed a cash box 38, preferably made of steel having an inclined sliding door 39 mounted between guides 40 and 41 at the sides of the cash box.

The rear guide 41 is in the form of a plate or partition, which extends from the upper part of the box downwardly and forwardly, as shown in Figure 3.

15 When the sliding closure member 39 is down, the cash box is closed, and when it is up, ready access can be had to the interior of the cash box.

20 In the guide and closure member 41 is an opening 42 through which projects a finger 43 on a trigger device 44 pivotally mounted on the inside of the cash box.

25 On the inside of the cash box adjacent to the trigger member 44 is a solenoid 45, having the armature 46. The solenoid 45 is connected by wires 47 and 48 with the battery 35 and a switch 49. The switch 49 is connected with the wire 33 by means of a wire 50.

30 As many switches may be provided as is desired.

In the diagram shown in Figure 6, I have shown a switch 51 located in a building at a distance from the bank. The switch 51 is connected by wires 52 and 53 with the wire 33 and the switch 36. The wire 53 is connected by a wire 54 with the wire 48.

35 Mounted adjacent to the side of the box 38 in a recess 55 by means of a pivot pin 56 is a catch 57, having a catch member or face 58 and a beveled face 59.

40 In the side edge of the sliding closure member 39 is a notch 60. The catch member 57 is held in substantially upright position, as shown in Figure 4 by means of an arm 61, which engages a flat spring 62.

45 In the rear surface of the sliding closure member 39 is a small notch 63 arranged to receive the finger 43 when the member 39 is raised, as shown in Figure 3.

50 In the practical use of my improved burglar proof device, the closure member for the bank door is raised as shown in Figure 1. The closure member 39 is raised, as shown in Figure 3.

55 In case a burglar should enter the bank, any employee or officer, who is near a switch can actuate the switch for closing the circuit. Switches can be placed on the floor or behind the counter or wherever it may be desired.

60 When any one of the switches, for instance the switch 49, is operated, a circuit will be closed.

65 When the switch 49 is operated, a circuit

will be closed from the battery 35 through the wire 47, the solenoid 45, the wire 48, the wire 50, the wire 33, the solenoid 31, the wire 34 and back to the battery. The armatures of the solenoids will be energized.

70 When the armature 46 is energized, the trigger 44 will be drawn toward the armature 46, which will draw the pin 43 from the opening 63. The closure member 39 will engage the beveled edge 59, so that the catch member 59 will permit the closure member to slide to closing position, whereupon the spring 62 will cause the engaging member 58 to enter the notch 60 for locking the closure member 39.

75 When the armature 31 is energized, the trigger 29 will be drawn out of engagement with the head 28, whereupon the weight 27 will drop upon the adjacent portions of the bars 22^a forcing them downwardly and forcing their outer ends upwardly out of engagement with the bars 16.

80 Thereupon the closure member 17 for the vault door will drop by gravity and be locked.

85 Thereafter the burglar will be shut out from access to the vault and the cash box.

90 It will be seen that my invention may be applied in a great variety of ways to fit the circumstances.

95 Switches may be placed in the manner and locations desired.

100 The operation of the closure member for the vault door would prevent the burglar from locking the employees of the bank in the vault.

105 The cash, which the bank employees are obliged to have on the counter for conducting current business should be kept in the cash box 38 in a cash drawer or the like, which can be readily placed in the cash box or removed therefrom at night and placed in the vault.

110 Some changes may be made in the arrangement and construction of the various parts of my device, without departing from the essential features and purposes of my invention, and it is my intention to cover by my claims, any modified forms of structure or use of mechanical equivalents, which may be reasonably included within their scope.

115 I claim as my invention:

1. In a device of the class described, a pair of foldable closure members, adapted when open to stand in raised positions where they tend to drop by gravity to position forming a closure, a pair of bars pivoted together and pivotally and slidably supported near their outer ends, so that when in substantial alignment their outer ends are frictionally held between the upper ends of the foldable closure members, a weight above the bars between their pivot supports, a trigger for supporting said weight, and an electric circuit including a solenoid and a

switch, whereby when the switch is closed the solenoid will be energized for moving the trigger for releasing the weight.

2. In a burglar proof equipment, a closure device comprising a pair of barred gate members, each consisting of an upright member designed to be secured to a wall or other support, a plurality of cross bars pivoted to said upright bar, a plurality of spaced upright bars pivoted to said cross bars, a notched latching bar pivoted to one of the last-named upright bars, and a pin adapted to coat with the notched bar for holding the gate in closed position.

3. In a burglar proof equipment, a closure device comprising a pair of barred gate members, each consisting of an upright member designed to be secured to a wall or other support, a plurality of cross bars pivoted to said upright bar, a plurality of spaced upright bars pivoted to said cross bars, movable means for holding said gate in open collapsed position, means for causing releasing movement of said last means, and means for automatically latching said gates upon their movement to closed position.

Des Moines, Iowa, July 22, 1921.

HENRY H. ALLISON.
